UNITED STATES PATENT OFFICE

FRANZ KURATE, OF CHICAGO, ILLINOIS, ASSIGNOR TO ECONOMY FUSE AND MFG. CO., OF CHICAGO, ILLINOIS, A CORPORATION OF NEW YORK

AUTOMATICALLY CONTROLLED HYDRAULIC PRESS INTENSIFIER

Application filed August 18, 1929, Serial No. 386,252.

This invention relates to improvements in automatically controlled hydraulic press intensifiers, and more particularly to improvements in hydraulic presses whereby an automatic control is provided to initially actuate the press at a low pressure and finally increase the pressure sufficiently high to perform the desired pressing operation.

Hydraulic presses such as used in molding operations are commonly operated by being connected to a low pressure fluid supply line. It is therefore necessary to use some arrangement of pressure intensifier which may comprise a slidable piston, the ends of which are of differential diameters whereby the low pressure acting upon the larger end will transmit a greatly increased pressure to fluid acting upon the ram of the press. It is not desirable immediately to apply the high pressure upon actuating the press, and therefore manually controlled valves have been provided so that the low pressure initially moves the press platen into engagement with the work, whereupon by a manual control the low pressure is admitted to the pressure intensifier, thus developing the high pressure on the ram. As stated, former constructions required two manual operations.

It is the purpose of this invention to improve upon the efficiency of apparatus of the type described, whereby the operator only needs to actuate one main valve, whereupon by automatic operation the ram will be moved into engagement with the work at a low pressure, and then the high pressure will be applied to perform the pressing operation.

It is a further purpose of the present invention to improve upon details of previous constructions by providing a minimum amount of high pressure piping resulting in a more compact apparatus with less liability of leakage or damage by bursting of the pipes.

Further and additional objects and advantages of my improvements will be more readily apparent from the following description taken in connection with the at-

tached drawing, in which a preferred embodiment is specifically shown.

In the drawing,

Figure 1 is a fragmentary sectional elevation through a portion of a hydraulic press illustrating the improved intensifier and the automatic control therefor the parts being shown in high pressure position with the press platen in engagement with the work.

Figure 2 is a fragmentary sectional elevation similar to Figure 1, but illustrating the parts in low pressure position.

In describing my invention, it will be understood that the apparatus is adaptable to many forms and arrangements of presses, and the piping connections may be considerably modified without departing from the spirit of my invention. Since the press may be of any conventional type, only a fragmentary showing has been made. Thus in the drawing, 10 is a fixed lower press platen, while 11 is an upper vertically movable press platen. It will be understood that the upper press platen is guided in any desired manner, and is preferably normally held by springs or other means in raised position. The piece of work shown in dotted lines is designated 12. Figure 2 shows the upper platen 11 in raised position, while Figure 1 shows the platen in engagement with the work 12.

A vertically slidable piston ram 13 is mounted for movement relative to a ram cylinder 14 which forms a portion of the press frame. The lower end of the ram 13 engages the movable platen 11. Packing 15 is pressed tightly in engagement with the sides of the ram 13 and prevents leakage of the high fluid pressure, the packing being retained by the flanged ring 16 which is bolted into the lower end of the cylinder 14. The cylinder 14 is closed at its upper end by a head 17, having an opening 18 extending therethrough. The upper portion of the opening is enlarged and screwthreaded as at 19 to provide a seat and means for attaching a housing forming a pressure intensifier 20. The intensifier 20 includes a cylinder 21 closed at the upper end by a head 22 and at its lower end by a cylindrical block 23. The cylindrical block 23

fits into the lower end of the cylinder 21 and is held in place by the pins 24. The heads of the pins 24 are covered by the sleeve 25 which seats against the head 17 of the ram cylinder. The block 23 includes a screw threaded extension 26 which fastens into the opening 19 and the block 23 is also formed with a narrow central opening 27 which leads into the opening 18 and thus into the chamber 28 above the ram 13. The block 23 is formed with a tubular recess 29 which is of a substantially smaller diameter than the main part of the chamber 30 within the cylinder 21. The two chambers of different diameters 29 and 30 are in communication and serve to guide a slidable piston 31. One end of the piston 31 extends to a head 32 and is of small diameter to be received in the chamber 29. The other end of the piston designated 33 is of larger diameter and slides in the chamber 30. Cup-shaped leather packing 34 is attached to the lower face of the head 32, and similar cup-shaped packing 35 is attached to the upper face of the head 33.

A fluid supply line 40 extends from some suitable source of low pressure fluid which may be preferably oil. Supply line 40 has connected therein, a T-connection 41 to which is attached the pipe 42. Adjacent the T-connection 41 is a check valve 43 which acts to allow the fluid to flow from the right to the left as shown in the drawing, but will prevent any backward flow of the fluid. To the left of the check valve 43 is a three-way valve 44 operated by the handle 45. To one side of the three-way valve is attached a return pipe 46 and upwardly extending from the valve 44 is a pipe connection 47. A short connecting pipe 48 threaded into a wall of the cylinder 14 communicates with an opening 49 which leads into the chamber 28 above the ram 13. Another connecting pipe 50 upon operation of the apparatus, constitutes an extension of the pipe 42 and is threaded into the head 22 of the intensifier cylinder 20, a suitable opening 51 being formed in the head 22. A return line 52 is connected to the opening 53 at the lower end of the chamber 30 and beneath the enlarged piston head 33 of the pressure intensifier. The return line 52 connects to the main return line 46 at the T-coupling 54. In line 52 is provided a T-coupling 55 to which is attached a pipe connection 56 which is in communication with the pipe 50 when the apparatus is not in use.

It will be understood that admission of low pressure through the pipe 48 will cause the ram 13 to force the platen 11 into engagement with the work and at the same time will impart an upward thrust to the piston 31. Admission of low pressure to the pipe 50 due to the difference in areas of the heads of the piston 31 will result in a greatly increased pressure being transmitted to the chamber 28 and thus cause the ram 13 to impart the

desired pressure to the work. It is desirable that the apparatus be automatic in its operation, whereby the operator will need only to move a main control valve. Thus, according to my invention, the operator places the work in position and then moves the main valve 44, whereupon the platen 11 will be moved into engagement with the work at a low pressure and by automatic operation the pressure will be brought up to a high working pressure. Upon completion of the pressing operation, the operator only needs to move the valve 44, whereupon the parts return to their initial position.

The automatic control comprises a floating piston generally designated 60 which is enclosed in a suitable casing 61. The casing 61 includes a chamber 62 of large diameter and a chamber 63 of small diameter. The piston 60 is formed with a left hand head 64 which tightly fits the large diameter chamber 62. To the right of the head 64 is a cylindrical portion 65 which closely fits the smaller chamber 63. The right hand head 66 of the piston 60 is of the same diameter as the cylindrical portion 65 and closely fits the chamber 63. Between the cylindrical portions 65 and 66 is a reduced neck 67. The left hand end only of the piston 60 requires to be sealed, and it is provided with a cup-shaped leather packing 68. The connection pipe 47 is threaded into the wall of the casing 61 and communicates with the duct 69 which leads into the chamber 62 to the left of the head 64. A similar duct 70 extends from the chamber 62 to communicate with the pipe 48 which is also attached to the casing 61. The pipe connection 42 is threaded into the right hand end of the casing 61 and communicates with a duct 71 extending to the extreme right hand end of the chamber 61 and a duct 72 which extends to an intermediate portion of the chamber 63. The pipe connection 50 is attached to the upper side of casing 61 at an intermediate point and communicates with the duct 73 which extends into the chamber 62 at a point between the duct 72 and the left hand end of the chamber 62. The return connection 56 is also attached to the casing 61 and communicates with the duct 74 at the point between the chambers 62 and 63. Cylindrical recesses 75 are provided in the interior of the casing 61 and connect with the ducts in order to permit free flow. A control valve 76 may be provided in the pipe line 42 and is actuated by the handle 77. This valve 76 may or may not be necessary or desirable. The operation of the apparatus will now be described.

The parts are shown in idle position in Figure 2, with the platen 11 in raised position. The valve handle 45 has been moved to an operative position, and will permit the oil pressure fluid supply to flow from pipe line 40 through the check valve 43 through

the valve 44, through the pipe connection 47, through the duct 69 to the chamber 62, through the duct 70 into the pipe 48 and from the pipe 48 directly into the chamber 28 behind the piston 13. The low pressure will serve to force the ram 13 downward against the resistance of the springs or other means which hold the platen 11 in raised position, and will force the platen into engagement with the work. At the same time, the low pressure will act upward against the lower head 32 of the intensifier piston 31 and will force the piston 31 from its lowered position shown in Figure 2 to the raised position shown in Figure 1. During this movement of the piston 31 the pipe line 52 is open to return while the pipe line 50 on the upper end of the intensifier chamber 30 is also open to return by communication through the duct 73 to the reduced neck portion 67 of the automatic piston 60. The reduced neck portion 67 is also in communication with the duct 74 and thus through the pipe 56 to the return pipe line 52. Therefore, there is no resistance to upward movement of the piston 31. At the same time the pipe line 42 will transmit low pressure to the right hand end of the chamber 63 which will be initially closed by the head 66 of the piston 60 which is in a position moved to the left hand end. As soon as the platen 11 is in engagement with the work, the low pressure will build up in the chamber 62 to the left of the head 64 and will finally be sufficient to move the piston 60 to the right, since the head 64 is of larger area than the head 66. The movement of the piston 64 may be manually controlled by the operation of the valve 76. Thus if the valve 76 is in closed position the piston 60 will not be moved. When the piston 60 is moved to the right, the parts will be in the position shown in Figure 1. The low pressure fluid supply will then flow through the pipe 42 through the duct 72 along the reduced neck portion 67 on the piston 60 through the duct 73 and through the pipe line 50 into the upper end of the intensifier chamber 30 and therefore act upon the large diameter head 33. A greatly increased pressure will therefore be developed by the small diameter head 32 and be transmitted to the chamber 28 and tend to force the piston 13 downward. The line 52 will still be open to return, but the pipe connection 56 will be closed by the movement of the cylindrical portion 65 of the piston 60 into the chamber 63. The high pressure will also act through the pipes 48 and 47 but will be stopped by the check valve 43 from flowing backward through the low pressure line.

It will therefore be apparent that the high pressure is confined to the ram chamber 28, the lower portion of the chamber 29 of the intensifier, the left hand end of the chamber 62 of the automatic valve and the pipe connec-

nctions 47 and 48. The packings 34 and 68 must therefore be sufficiently tight to prevent leakage. The high pressure will act and cause the pressing operation to be carried out. Upon completion, the operator moves the valve 45 in order to open pipe line 47 to return through the pipe 46. The pressure will therefore be relieved from above the ram 13 and the ram will be returned to its upward position by any means such as springs. The release of the pressure at the left hand of the piston 60 will allow the piston 60 to be forced to the position shown in Figure 2, and the piston 31 will then be open to return on each side and will therefore drop to the position shown in Figure 2. The parts will then be in position for another operation.

Various modifications and changes may be resorted to in adapting my invention to conditions of use, without departing from the spirit and scope of my invention as expressed in the appended claims.

I claim:

1. Apparatus for carrying out pressing operations comprising a press cylinder, a low pressure fluid supply, a fluid supply line leading from said low pressure supply to said cylinder, means in said line controlling the flow of fluid therethrough, a pressure intensifier associated with said press cylinder and arranged to transmit high pressure to said cylinder upon the admission of low pressure to said intensifier, a fluid supply line leading from said low pressure supply to said intensifier, means for controlling the flow of fluid through said last mentioned line, said last named means being associated with the fluid supply line to said cylinder to be automatically operated upon the admission of low pressure to said cylinder and additional manually adjustable means in the supply line to said intensifier to control the rate of actuation of said intensifier.

2. Apparatus for carrying out pressing operations, comprising a press cylinder, a low pressure fluid supply, a fluid supply line leading from said low pressure line to said press cylinder, a manually operated valve in said supply line, a pressure intensifier associated with said press cylinder and including a differential piston arranged to receive low pressure at one end and to transmit high pressure from the other end to said press cylinder, a fluid supply line leading from said low pressure supply to said intensifier, an automatically shiftable plunger associated with both of said supply lines and arranged to control the admission of low pressure to said intensifier, said plunger being operated upon the admission of low pressure to said press cylinder and a manually operated valve in the supply line between said shiftable plunger and the low pressure supply arranged to control the speed of movement of said shiftable plunger.

3. In a hydraulic press, a main pressure cylinder, a ram movable therein, a low pressure fluid supply line leading to said main cylinder, a check valve in said fluid supply line preventing back flow at any time, an auxiliary cylinder, a differential piston slidable therein having a large head at one end and a small head at the other end, a fluid passage leading from the end of the auxiliary cylinder guiding the small end of the differential piston to the main cylinder, a low pressure fluid supply line leading to the end of the auxiliary cylinder guiding the large end of the differential piston, a valve controlling the flow of the fluid through said last-mentioned supply line, means for automatically opening said valve when the pressure in the main cylinder reaches a predetermined amount and additional means for controlling the rate of automatic operation of said valve whereby the movement of the differential piston produces a pressure in said main cylinder and upon said ram greater than the pressure of the low pressure fluid supply.

4. In a hydraulic press, a main pressure cylinder, a ram in said cylinder, a pressure intensifier having its high pressure side in communication with said main cylinder, a low pressure fluid supply line leading to said main cylinder, a branch fluid conduit leading from said supply line to the low pressure side of said intensifier, a check valve in said supply line between the said branch conduit and said main cylinder preventing back flow of the fluid at any time, a differential piston valve normally held in position by the fluid pressure in said branch conduit acting on the small end of said piston valve, said piston valve in normal position closing said branch conduit to prevent actuation of said intensifier and being exposed at its large end to the pressure developed in said main cylinder whereby the development of a predetermined pressure in said main cylinder causes automatic shifting of said piston valve to permit actuation of said intensifier and a manually adjustable valve in said branch conduit between said supply line and said piston valve for controlling the rate of shifting movement of said valve.

5. In a hydraulic press, a main pressure cylinder, a ram in said cylinder, a pressure intensifier having its high pressure side in communication with said main cylinder, a low pressure fluid supply line leading to said main cylinder, a branch fluid conduit leading from said supply line to the low pressure side of said intensifier, a check valve in said supply line between the said branch conduit and said main cylinder preventing back flow of the fluid at any time, a manually-operable two-way valve between said check valve and said main cylinder, a drain leading from said two-way valve, a differential area piston valve exposed at its small end to the pres-

sure in said branch conduit and exposed at its large end to the pressure in the fluid supply conduit between said two-way valve and said main cylinder, said piston valve being normally urged into position to close said branch conduit to prevent actuation of said intensifier and adapted to be automatically shifted to open said branch conduit upon the development of a predetermined pressure in said main cylinder, the shifting movement of said piston valve causing a back flow of fluid in said branch conduit towards said fluid supply line and a manually operable valve for controlling the back flow of fluid in said branch conduit to control the rate of shifting movement of said piston valve.

Signed at Chicago, Illinois, this 12th day of August, 1929.
